UNITED STATES PATENT OFFICE.

LUDWIG SCHÖN AND JAKOB PFRETSCHNER, OF ESSEN, GERMANY, ASSIGNEES TO
FRIED. KRUPP AKTIENGESELLSCHAFT, OF ESSEN-ON-THE-RUHR, GERMANY.

OVERLOAD SWITCH.

Application filed September 4, 1920. Serial No. 408,383.

(GRANTED UNDER THE PROVISIONS OF THE ACT OF MARCH 3, 1921, 41 STAT. L., 1313.)

To all whom it may concern:

Be it known that we, LUDWIG SCHÖN, residing at Essen, Germany, and JAKOB PFRETSCHNER, residing at Essen, Germany, both citizens of the German Republic, have invented a certain new and useful Improvement in Overload Switches (for which patents have been granted in the following countries: Germany, No. 379,739, filed June 10, 1917; Austria, No. 88,510, filed September 26, 1918; Switzerland, No. 87,295, filed April 30, 1920; Holland, No. 7,135, filed May 14, 1920; Sweden, No. 49,664, filed June 19, 1920; Spain, No. 74,424, filed July 3, 1920; 15 France, No. 523,357, filed July 7, 1920; and Italy, No. 25/548, filed July 8, 1920), of which the following is a specification.

This invention relates to overload switches having a power storing device and a magnetic field adapted to be excited both by the current of the circuit which is to be protected and by an auxiliary current. The object of the invention is to provide an overload switch of the type above referred to 20 which shall be suitable for every kind of current A. C. or D. C. and which possesses the property of not being able to switch itself in again after the removal of the disturbing cause but on the contrary remains 25 open until the auxiliary circuit is opened by hand. The device is distinguished by simplicity of construction convenience of manipulation and great reliability of action.

The invention will be described with reference to the accompanying drawings, in which—diagrammatically

Figs. 1 and 2 show a circuit arrangement for protecting a direct current supply circuit.

Fig. 3 shows a similar arrangement applied to a Leonard motor generator set.

In the first form shown in Figure 1 it is assumed that a translating device (not shown), such as a continuous current motor for example, though the embodiment is not limited to direct current, is to be protected from overload by the overload switch. In this figure A denotes the main current winding, A¹ the magnet core and A² the 45 contact brush of a direct acting electro-magnetic switch rigidly connected to the core of the magnet. A³ is a tension spring, which tends to put the contact brush A² into con-

tact with two contact blocks A⁴ and A⁵ attached to the conductor to be interrupted. Upon the core A¹ of the magnet is mounted in addition to and in parallel with the main current winding A and with the interruption points A⁴, A⁵ in series therewith, an auxiliary winding A⁶. In the main current circuit is also provided a two pole hand operated switch B, which serves to cut off the current from the current consumer and from the auxiliary winding A⁶ at the same time. The automatic switch consisting of the parts A, A¹ to A⁶ is enclosed in a casing (not shown) closed on all sides.

The two magnet windings A and A⁶ which act in the same direction upon the magnet core A¹ are so proportioned and arranged that their common pull in the direction in which the switch is opened is less than the oppositely directed pull of the spring A³, so long as the main current winding is traversed by the normal or a smaller current, 75 but that their pull overcomes the power of the spring as soon as a non-permissible high current strength arises in the main current circuit, that is to say, in the circuit of the current consumer. The auxiliary winding A⁶ is so proportioned that its pull alone will suffice under complete excitation to hold the switch open with the contact brush A² away from the contact blocks A⁴ and A⁵, in the position shown in Figure 1, but it 80 cannot open the switch when in the closed position without the co-operation of the main current winding A traversed by a non-permissible high current, because when the switch is closed the auxiliary winding A⁶ 85 is practically short-circuited by way of A, A².

In considering the working of the arrangement let it be assumed that both the automatic switch A², A⁴, A⁵, as well as the hand operated switch B are in closed position, so that the translating device receives current from the source. If now, for example, say by overloading of the motor, an overload arises in the circuit of the translating device, the switch A², A⁴, A⁵, opens under the action of the main current winding A.

As the counter electromotive force of the motor or the like disappears rapidly as soon 100 as the circuit containing the main current

winding A is interrupted, the auxiliary winding A⁶, after the switch A², A⁴, A⁵, is opened receives the full potential from the source of current, so that it will be fully excited and is able to hold the switch fast in the open position.

After the removal of the disturbing cause the switch B is first opened by hand, whereby the current is cut off from the winding A⁶ and the switch A², A⁴, A⁵, again closes itself under the action of the spring A³. The switch B can now be closed and the motor started up again. The switch A², A⁴, A⁵, then remains closed provided the disturbance is finally removed, otherwise it immediately opens again.

The arrangement shown in Figure 2, which is particularly adaptable among other things to protect a continuous current generator supplying a main differs from the one above described by the fact that the auxiliary winding A⁶ is connected through a switch C, which is conveniently constructed as a push switch, to the two sides of the main, supplied by the continuous current generator and that the hand operated switch B is therefor dispensed with. If the switch A², A⁴, A⁵, and likewise the switch C are in closed position, both magnet windings A and A⁶ are excited.

If now the current strength in the main current circuit rises for any reason to an excessive degree (e. g. owing to a short circuit on the main), the switch A², A⁴, A⁵, is opened as shown under the action of the tractive force of both, windings A and A⁶, which overcomes the power of the spring. In order to again close the switch A², A⁴, A⁵, after the removal of the disturbing cause, it is only necessary to temporarily interrupt the current in the auxiliary winding A⁶ by opening the switch C. This cuts the current off from the auxiliary winding A⁶ and the switch moves into its closed position. If contrary to expectation a non-permissible high current still prevails, the switch A², A⁴, A⁵, immediately opens again, whereas it remains closed if the current in the meantime has dropped to the permissible value. It may be stated that when dealing with alternating current circuit coils A and A⁶ are not necessarily arranged to have the same magnetic circuit though they may employ the same yoke.

Figure 3 shows a form of the switch suitable for working with a Leonard motor-generator set.

In this case the main current winding is included in the common armature circuit of the Leonard generator D and the motor E belonging thereto. The switch A², A⁴, A⁵, on the other hand is included in the exciting circuit of the generator D. The auxiliary winding A⁶ is connected through a switch F to the source of current of con-

stant tension which supplies the exciting current.

The working of the apparatus is similar to that of the arrangement shown in Figure 2. The difference is that the current is cut off from the armature circuit without it being necessary to interrupt the circuit.

If the automatic switch is to protect the Leonard motor generator set against current impulses also, in which the direction of the current in the armature circuit is reversed, as happens when the motor E is braked electrically, it is convenient to construct the switch with separate magnetic circuits for the main current winding and for the auxiliary winding. As the auxiliary winding A⁶ is so proportioned that its magnetic tractive force is sufficient in all cases, to hold the switch in open position, variations in the strength of the magnetic field of the main current winding A are not able, when separate magnetic circuits are employed, to bring the switch into closed position. This prevents any premature closing owing to the reversal of the current in the main current winding.

Claims:

1. An overload switch device for protecting an electric circuit, comprising means tending to close the switch, a main circuit whose current is controlled by the operation of the switch, an auxiliary circuit whose current is permitted to flow independent of said switch control, means dependent upon the simultaneous flow of excessive main and of the auxiliary current, for opening said switch against said closing means, but adapted to retain the switch in open position by the auxiliary current alone then flowing, the relation of the force of said switch closing means to the magnetic tractive force exerted by the current traversing said auxiliary circuit being so determined that the switch remains in its open position until said auxiliary circuit is broken.

2. An overload switch device for protecting an electric circuit, comprising means tending to close the switch, a main circuit whose current is controlled by the operation of the switch, an auxiliary circuit whose current is permitted to flow independent of said switch control, means dependent upon the simultaneous flow of excessive main and of the auxiliary current, for opening said switch against said closing means, but adapted to retain the switch in open position by the auxiliary current alone then flowing, the relation of the force of said switch closing means to the magnetic tractive force exerted by the current traversing said auxiliary circuit being so determined that the switch remains in its open position until said auxiliary circuit is broken and means for cutting off at will the aux-

iliary current supply to permit the closing of said switch.

3. An overload switch device for protecting an electric circuit, comprising means tending to close the switch, a main circuit whose current is controlled by the operation of the switch, an auxiliary circuit whose current is permitted to flow independent of said switch control, means dependent upon the simultaneous flow of excessive main and of the auxiliary current, for opening said switch against said closing means, but adapted to retain the switch in open position by the auxiliary current alone then flowing, the relation of the force of said switch closing means to the magnetic tractive force exerted by the current traversing said auxiliary circuit being so determined that the switch remains in its open position until said auxiliary circuit is broken, and means for cutting off at will the auxiliary current supply to permit the closing of said switch, said cutting-off means being inserted in said main circuit.
- 25 4. In combination, a main circuit, an electric switch inserted therein, a mechanical means normally tending to close said switch, electromagnetic means comprising a main and auxiliary element for opening said switch against the action of said mechanical means on a predetermined current flow pass-

ing through both of said elements whereby said main element is disconnected, said auxiliary element being adapted to maintain said switch in open position against the action of said mechanical means, and means for cutting off at will the current supply to said auxiliary element.

5. In combination with an electric switch, a mechanical means normally tending to close said switch, electromagnetic means comprising a main and auxiliary element for opening said switch against the action of said mechanical means on a predetermined current flow passing through both of said elements whereby said main element is disconnected, said auxiliary element being adapted to maintain said switch in open position against the action of said mechanical means, and means for cutting off at will the current supply to said auxiliary element, said cutting-off means being inserted in the circuit common to the main and auxiliary elements of said electromagnetic means.

The foregoing specification signed at 55
Essen, Germany, this 18th day of May, 1920.
